[57] CLAIM

The ornamental design for a pet food bowl, as shown
and described.

DESCRIPTION

FIG. 1 is a top and partial front and side perspective
view of a pet food bowl, showing my new design;

FIG. 2 is a top plan view thereof;

FIG. 3 is a front elevational view thereof;

FIG. 4 is a left side elevational view thereof, the right
side elevational view thereof being a mirror image of
the left side elevational view;

FIG. 5 is a rear elevational view thereof; and,

FIG. 6 is a bottom plan view thereof.
